UNITED STATES PATENT OFFICE.

WILLIAM HERBERT HALL, OF OSHAWA, ONTARIO, CANADA, ASSIGNOR TO THE PEDLAR PEOPLE LIMITED, OF OSHAWA, ONTARIO, CANADA.

METALLIC SHINGLE.

1,218,399.

Specification of Letters Patent.

Patented Mar. 6, 1917.

Application filed November 2, 1915. Serial No. 59,317.

To all whom it may concern:

Be it known that I, WILLIAM HERBERT HALL, a subject of the King of Great Britain, and resident of Oshawa, in the Province of Ontario, Dominion of Canada, have invented certain new and useful Improvements 5 in Metallic Shingles, of which the following is the specification.

This invention relates to improvements in 10 metallic shingles of the type adapted to interlock all around, and the objects of the invention are to provide for the continuity of the bottom lock and to improve the side lock and render the same more effectively water 15 tight, and it consists essentially of the improved construction hereinafter described in detail in the accompanying specification and drawings.

In the drawings,

20 Figure 1 is a perspective view of the shingle embodying the present invention.

Fig. 2 is a longitudinal section through two shingles connected.

25 Fig. 3 is a transverse section through two shingles connected.

Fig. 4 is a plan view of the blank from which the shingle is formed.

Fig. 5 is a perspective detail of the lower corner of the shingle.

30 Fig. 6 is a perspective view of the upper corner of the shingle.

Fig. 7 is an enlarged sectional detail through the side joint.

In the drawings like characters of reference indicate corresponding parts in all the figures.

Referring to the drawings, A represents the body portion of the shingle which may have any convenient design embossed or 40 otherwise formed thereon. As illustrated, a plurality of parallel flutings 10 are formed in the face of the shingle adapted to strengthen the same and distribute the water drainage over the same. The bottom of each 45 shingle is also formed with a transverse molding 11 into which corresponding moldings 12 and 13 on the upper part of the next shingle are adapted to fit to thereby assist in holding the shingle in place and form a 50 water barrier.

The side lock on the adjacent shingle is formed by a trough shaped flange 14 on one side of the body portion of the shingle adapted to receive a corresponding tongue shaped flange 15 on the opposite side of the shingle. 55

In accordance with the present invention the bottom of the trough shaped flange 14 is substantially on a level with the bottom of the body portion and the trough shaped flange is formed with a longitudinally extending ridge 16 which extends upwardly well above the top surface of the body portion and is adapted to fit into a corresponding longitudinally extending recess 17 formed in the tongue shaped flange 15. 60 65

This interlocking ridge and recess is an important feature of the invention as it prevents any leakage of water on the side joint and forms a water barrier between adjacent shingles. It projects substantially 70 above the surface of the body portion, that is to say above the planes of the tops of the flutings 10, and it will also be observed that the bottom of the trough shaped flange does not project below the plane of the lower 75 edges of the flutings. In this way a more substantial bearing on the roof is maintained.

Previously in many forms of shingles the trough shaped flange projected below 80 the surface of the shingle which caused the body portion of the shingle to be supported above the roof rendering it liable to be bent easily by pressure from the outside.

The top and bottom lock are formed by 85 an undeturned flange 20 on the bottom of the shingle adapted to engage an overturned flange 21 on the top of the shingle, both of said flanges being hook shaped in form.

To provide a continuous bottom joint, a 90 portion of the trough shaped flange 14 and the tongue shaped flange 15 are turned up to correspond with the flange 20 to thereby enable this undeturned flange to extend in a continuous manner across the body portion of the shingle and across both the trough shaped flange and the tongue shaped flange as clearly shown in Fig. 5 of the drawings.

On the upper end of the shingle the overturned flange 21 is bent at the side 23 into engagement with the trough shaped flange and the top portion 25 of the trough shaped flange is extended and bent upwardly 100 slightly to form a water stop as shown in 105 Fig. 6 of the drawings.

What I claim as my invention is:

1. A metallic shingle having a trough shaped flange formed on one side with a ridge projecting upwardly above the surface 110

of the shingle and having a tongue shaped flange on the opposite side adapted to enter the trough shaped flange of a corresponding shingle, said tongue shaped flange having a recess therein to receive the ridge in the trough shaped flange and a water stop formed at the top of the trough shaped flange formed by turning upwardly a projecting portion of the flange.

10 2. A metallic shingle having side joints below the plane of the surface of the shingle, being also formed with interlocking top and bottom joints, the surface of the shingle being formed with a plurality of par-

allel fluting extending across the whole 15 width of the same and from top to bottom thereof; the depth of said fluting being substantially equal to the depth of the side joints, whereby the lower surface of the fluting may rest on the roof or other support for the shingle and so support the face of the shingle therefrom.

In witness whereof I have hereunto set my hand in the presence of two witnesses.

WILLIAM HERBERT HALL.
